UNITED STATES PATENT OFFICE

WILFORD R. SPROUL, OF CHICAGO, ILLINOIS, ASSIGNOR TO E. W. SPROUL CONSTRUCTION COMPANY, OF CHICAGO, ILLINOIS, A CORPORATION OF ILLINOIS

CONCRETE BUILDING CONSTRUCTION

Application filed March 23, 1928. Serial No. 264,052.

This invention relates to concrete building construction, particularly to such construction of the monolithic type wherein the walls are built up by successive pourings of concrete that unite in setting. It is concerned primarily with devices for the building of such structures by the use of so-called slip forms, that is, forms which are gradually elevated as the wall is built up, to afford the molds for the successive pourings one on top of another.

The present invention is concerned primarily with the construction of walls in such fashion, with suitable voids or recesses for the accommodation and tying in of floor slabs, brackets, or other elements of the building structure which are placed after the wall is formed.

A general object of the invention is the provision of certain improved devices which may be employed in connection with the use of slip forms, without involving changes in the construction of the forms or complications in their handling and which will result in the accurate and definite locating and proper forming of recesses and the like for the accommodation and tying in of other structural parts.

Another object is the provision of such devices by employment of which the amount of labor required will be minimized and substantial savings effected in the cost of the construction operations.

Another object is the provision of such devices, which will accommodate a desired variety in the locating of reinforcing elements in the concrete structure.

Other and further objects will be pointed out or indicated hereinafter, or will appear to one skilled in the art on an understanding of the invention or its employment in practice.

In the accompanying drawing forming a part of this specification I show various forms of devices and structures, these being presented by way of illustration for facilitating an explanation of the invention, but it is to be understood that the invention is not confined for its embodiment or practice to these particular examples.

In said drawings

Fig. 1 is a part sectional elevation of a building wall, in process of erection, taken transversely therethrough and illustrating the placing of a floor joint form;

Fig. 2 is a perspective view illustrating an improved floor joint form;

Fig. 3 is a part sectional elevation of a wall, taken transversely therethrough, and illustrating the employment of a floor joint form and a bracket joint form in conjunction and in association with various reinforcing and tying rods, and

Fig. 4 is a similar sectional elevation showing the wall in conjunction with a portion of the floor slab and a bracket.

In one procedure followed in the building of monolithic concrete walls, slip forms are employed which form the mold faces for the inner and outer wall surfaces, and which are elevated, step by step, after successive pourings of concrete. These slip forms are usually carried on jack rods which constitute reinforcing elements extending vertically in the wall, said jack rods and the subjacent completed portions of the wall affording guidance for the forms such as to maintain them in a position where they will hold subsequent pourings to continue the wall on up in the desired plumb disposal. Where it is desired to tie in the edges of floor slabs, or other structural portions, or set such parts into the area of the wall, it becomes necessary, if such portions are to be installed after the wall has been poured, to provide recesses and anchoring members in the wall in the course of its erection. Such recesses must be accurately placed, and they must make provision for tying connections of reinforcing members between the wall and these other parts of the structure. Moreover, to avoid interference with the systematic and accurate elevation and guidance of the slip forms, the operation of devices for the forming of the recesses must be such as can be conveniently employed within the mould cavity afforded by the forms.

The present invention provides devices coming within these qualifications and contributing other and further advantages. For an explanation of the invention, I will refer

to the examples shown in the accompanying drawing. Here the reference numeral 10 designates a portion of a wall under construction, which portion is formed of concrete with the desired reinforcements, and may be regarded as having set to the rigidity necessary to afford the guidance for the slip forms. Two of the form panels are illustrated at 11 and 12, same forming the mold faces for the inner and outer surfaces of the wall, respectively. In Fig. 1 these are shown in a position to accommodate a further pouring of concrete within the mold space M. In Fig. 2 is illustrated a portion of a joint form, which is employed, where desired, as an auxiliary to the slip form, to provide a recess in the wall. This joint form is made up of top and bottom planks 14 connected in parallel relationship by spacers 14^a and having a length of wire mesh 14^b stretched across and secured to their edges at one side. Thus a trough-like structure is provided, open at the front and having a wire mesh wall at the back. At suitable intervals the planks are provided with apertures 14^c, for accommodation of reinforcing or tie rods. The wall 10 having been built up to an elevation where it is desired to form a recess, joint forms of the sort just described are placed within the mold space between the form panels 11 and 12 and, in the event the recesses are for the accommodation of floor slabs, said joint forms are arranged in the proper level disposal, and with their open side in contact with the inner form panel. For a floor joint, these joint forms may be of such width that they extend for only a part of the wall's thickness, the mesh side 14^b thus being within the cross sectional area of the wall. Reinforcing or tie rods 15, extending vertically in the wall, are accommodated by the apertures 14^c, said rods being placed either before or after the positioning of the joint forms and being partly imbedded in the concrete, whereby they hold the joint form against the form panel. When the joint forms are thus suitably placed, the next pouring of concrete is placed between the form panels 11 and 12, the joint form being enveloped therein at the top and on the screen side. The wire mesh is of such size as to prevent the flow of the concrete therethrough to any appreciable extent. However, some of the finer or more fluid parts of the mixture do penetrate the screen, bonding it into the concrete, and holding it definitely in place, thus counteracting the tendency of the joint form to float out of place in the concrete while the latter is plastic. When the new pouring is set sufficiently, and the time comes to elevate the slip form, such is accomplished in the usual fashion, without any disturbance of the joint form, which remains in place, for the time being, in the wall. When the wall has been thus built up

to the desired height, the planks 14 and spacers 14^a may be torn out, the planks being split longitudinally along the line of the apertures 14^c and removed from the wall, leaving the wire mesh bonded in the concrete. Thus a groove or recess is formed in the face of the wall, with the rods 15 exposed in the recesses for the connection of tying reinforcements of a floor slab which is subsequently to be poured.

In Fig. 3 is illustrated an arrangement of joint form for forming the recesses completely through the wall, as for the accommodation of a floor bracket. This joint form is built of boards as a rectangular open sided box, one of the side boards being illustrated at 16 and the end boards at 17. The length of the latter is such as to equal the thickness of the wall, and their width is such as is necessary for the width of the recess. The end boards are provided with apertures 17^b, for accommodation of the reinforcing and tie rods 15'. These joint forms are placed between the slip form panels, as above described, and in the desired locations, wherein they are anchored by the rods. It will be observed that certain of the rods passing through the bottom board, terminate short of the top board. These remain in this position until after the wall has been built up at the sides and above the joint form and properly set, whereupon the boards 16 and 17 may be torn out, and the ends of the rods terminating within the recesses may then be bent out to positions illustrated in Fig. 4 when the forms are subsequently placed for the bracket 18.

Fig. 4 shows the relationship of the floor slab 19 and the bracket 18 with respect to the wall originally formed with recesses in the manner above described. It will be observed that the rods 15' form a bonding tie between the bracket and the wall 10, and that the slab tying or reinforcing rods 20 are hooked onto the rods 15, these being placed preliminary to the pouring of the slab. It also will be understood that the forms for the slab and the bracket are so associated with the recesses in the wall that at the pouring of the bracket and the slab, a portion of the concrete will flow into said recesses and in this fashion, when the concrete is set, afford a bonded connection and support for the slab and the bracket.

From the foregoing description it will be apparent that the joint forms may be placed as desired without involving any interference or complications in the manipulation or construction of the slip forms. Further advantages reside in the fact that joint forms of this type accommodate a desired variety in the placing of the reinforcing members, and also act as spacers for the reinforcing members with respect to the slip form panels, and also are retained definitely in posi-

tion by virtue of their cooperation with the rods and with the slip forms, when the concrete is being poured and distributed. A further very important advantage lies in the readiness with which the joint forms may be removed after the wall has set. The wrecking or tearing out of these joint forms is a procedure requiring hand labor, and if such forms are difficult of removal, may involve considerable expense. The joint forms herein disclosed have the advantage of being very easily removed, as the spacers may readily be knocked out and the boards pried loose from the concrete and split longitudinally to free them from the rods. This advantage appears particularly in the case of the floor joint forms, where it is necessary simply to remove the spacers and the top and bottom planks, the screen, which form the back retaining wall of the recesses, being left bonded in the concrete.

What I claim is:

1. As an article of manufacture, a joint form for concrete construction comprising a trough-like frame having oppositely disposed walls formed of planks provided with longitudinally spaced apertures, and a wall of wire mesh conjoining margins of said oppositely disposed walls, said wire mesh being of a size to retain concrete mixture.

2. A joint form for concrete construction comprising a three-sided trough-like frame, the opposite sides of the frame being formed of planks spaced apart and connected in parallel relationship, and the third side being formed of wire fabric conjoining said opposite sides and of a mesh size effective to retain concrete mixture from passing through into the space between the planks.

3. A joint form for concrete construction comprising a trough-like frame having opposite sides formed of planks maintained in a definite spaced relationship and a third wall formed of wire fabric stretched between said opposite sides and of a mesh size effective to dam unset concrete mixture.

4. Means for concrete building construction comprising, in combination, form panels arranged in opposite disposal to afford mold faces for a wall, a joint form arranged between the panels within the cross sectional area of the wall, said joint form having oppositely arranged sides spaced apart and positioned with their margins against one of the form panels and a wall portion formed of wire mesh stretched between said wall portions and spaced apart from said panels, and rods extending through the joint form between said panel and said mesh wall.

50 In testimony whereof I have hereunto subscribed my name.

WILFORD R. SPROUL.
